INVENTOR

A detailed diagram of a classical column capital, likely Ionic, with various parts labeled. The capital is shown in a three-quarter view, with the main body being the abacus and the decorative top being the volute. Labels include: A (the top of the abacus), B (the necking), C (the volute), D (the necking), E (the necking), F (the necking), G (the necking), H (the necking), I (the necking), J (the necking), K (the necking), L (the necking), M (the necking), N (the necking), O (the necking), P (the necking), and Q (the necking). The diagram is oriented vertically, with the top of the capital pointing upwards.

N. PETERS, Photo-Lithographer, Washington, D. C.

UNITED STATES PATENT OFFICE.

THOMAS L. RIVERS, OF MOUNT VERNON, ILLINOIS, ASSIGNOR OF ONE-THIRD
TO EDWARD M. SHEPHERD, OF SAME PLACE.

HINGE.

SPECIFICATION forming part of Letters Patent No. 276,540, dated April 24, 1883.

Application filed January 5, 1883. (Model.)

To all whom it may concern:

Be it known that I, THOMAS L. RIVERS, a citizen of the United States, residing at Mount Vernon, in the county of Jefferson and State 5 of Illinois, have invented a new and useful Hinge, of which the following is a specification, reference being had to the accompanying drawings.

This invention relates to hinges of that class 10 which are double-jointed and non-projecting; and it consists in certain improvements in the construction and arrangement of parts.

In the drawings, Figure 1 is a plan view of a joint having my improved hinge. Fig. 2 is 15 a like view taken from the inner side. Fig. 3 is a transverse sectional view thereof. Fig. 4 is an end view of the hinge detached.

Referring to the drawings, A designates the hinge, which is formed with a back plate, B, 20 to which is hinged at each side edge, C C, a plate, D, by which the hinge is secured in position. These joints E at the junction of the back of the hinge and the securing-plates at each side, may be formed in any ordinary or 25 suitable manner.

To the outer face of each securing-plate D is secured an auxiliary plate, F, having its edge projecting from the plate D at its joint E, so as to form a flange, G, as shown. This flange 30 G forms a stop to the movement of the plate D, to which it is secured, by engaging the back plate, B, when the hinge is turned to the position shown in dotted lines, Fig. 3 of the drawings, and, by reason of this engagement, 35 causes the joint E at the other side of the hinge to operate when it is desired to turn the hinge to the position shown in dotted lines, Fig. 4 of the drawings.

H designates a T-plate, the stem I of which 40 extends between the joints E E, while its head J forms an interior plate corresponding to the plate B. The head J of the T-plate is of sufficient width to enable its side edges, K K, to form stops for the securing-plates D D when 45 the hinge is closed; and by reason of this engagement with the said plates D D the hinge will close squarely and neatly, and the plates D D cannot be forced further inwardly by the weight of the boards or strips to which the 50 hinge is secured.

My improved hinge is secured to the adjoining edges L L of the portions M M, to be hinged

together by screws N or their equivalent, which pass through the securing-plates D D, a plate, O, being also preferably interposed between the heads of the screws and the inner surface of the plate D. Mortises P P are formed, one in each edge L, to receive the half of the hinge at that side. 55

The operation and advantages of my invention are obvious. The hinge is simple and durable in construction, and it can be manufactured at a comparatively minimum cost. 60

It is evident that the flange G can be formed integral with the securing-plate D, in which 65 case the plate F is dispensed with.

I am aware that hinges of this double-jointed non-projecting construction have been heretofore made with a back plate to which are hinged the securing-plates, which latter are 70 provided with lugs that engage the back plate, such a construction and arrangement being shown in the patent to Pfantz and Franck, No. 255,809, April 4, 1882.

I am also aware of the patent to Morgan, 75 No. 232,747, September 28, 1880; but I do not wish to be understood as claiming broadly the invention embodied in either of these patents, my claim being for my own novel construction and arrangement of parts. 80

I claim as my invention—

An improvement in non-projecting hinges, the combination of the back plate, B, the plates D D, hinged to each side the plate B, and serving to secure the hinge in position, the 85 flanges or extensions G, projecting above the plates D D, and arranged to engage the outer face of the back plate, B, and the T-plate H, having its head J, forming an interior plate, 90 extending across the hinge from side to side, and serving to provide stops for the plates D D when the hinge is closed, and having its stem I extending up between the joints of the plate B and plates D D to the former, and 95 serving to secure the said back plate and interior plate or head J together, as set forth.

In testimony that I claim the foregoing as my own I have hereto affixed my signature in presence of two witnesses.

THOMAS L. RIVERS.
